UNITED STATES PATENT OFFICE.

FRED A. PUTNAM, OF MELROSE, MASSACHUSETTS.

PRINTING-MACHINE.

1,208,832.

Specification of Letters Patent. Patented Dec. 19, 1916.

Application filed September 14, 1911. Serial No. 649,234.

To all whom it may concern:

Be it known that I, FRED A. PUTNAM, a citizen of the United States, residing at Melrose, county of Middlesex, State of Massachusetts, have invented an Improvement in Printing-Machines, of which the following description, in connection with the accompanying drawing, is a specification, like characters on the drawing representing like parts.

This invention relates to printing machines which are adapted to print an impression on leather, cloth, or other similar sheet material, and the objects of the invention are to provide a novel printing machine by which repeated impressions can be made with extreme rapidity and by which the printing surface can be applied to the material to be printed with a high pressure. I attain these objects by employing a rotary printing member carrying the printing surface and the device is constructed so that this rotary member is not only a printing member, but is also a feeding member so that by its rotation it operates both to feed the material to be printed and apply the impression thereto.

I prefer to make the printing member with a plurality of adjustable type members, each having a plurality of printing characters thereon, so that by adjusting the various type members the character of the impression may be varied. These type members are shown in the form of type disks and are carried by the printing member so as to turn about an axis extending transverse to the axis of rotation. The arrangement is such that the operative characters of the type disk stand substantially in the line of the periphery of the member of the rotating member so that as the member is rotated the characters one after the other will be brought into contact with the work and thus the impression is progressively made.

I have illustrated herein one simple embodiment of my invention which is sufficient to show the principle thereof, but I wish it understood that the constructional details may be varied in many ways without departing from the invention.

In the drawings, Figure 1 is an end view of a printing machine embodying my invention with a portion of the frame broken out; Fig. 2 is a vertical section through the frame, said section passing through the rotary printing member on substantially the line $\alpha-\alpha$, Fig. 1; Fig. 3 is a perspective view of one of the type disks; Fig. 4 shows an implement which may be used for adjusting the type disks separately.

The rotary printing member is shown at 1 and may have any suitable shape or construction. It is shown as mounted on a shaft 2 which is suitably journaled in a bearing 3 sustained by a frame or base piece 4. The shaft 2 may be driven in any suitable way without departing from the invention. I have herein shown said shaft as having thereon a gear wheel 5 which is adapted to mesh with and be driven by a suitably-sustained driving gear (not shown), although it would be within my invention to apply a driving pulley directly to the shaft.

The printing member 1 carries one or more printing or type members 6 which carry type 7 that are adapted to be brought into the line of the periphery of the member 1. These type members 6 may be constructed in various ways without departing from the invention. I prefer, however, to make them in the form of disks, as shown in Fig. 3, which are provided on their periphery with separated type or printing characters 7. I will also preferably make each disk 6 with a notch 8 between adjacent type. These type disks 6 are mounted in a recess 9 formed in the printing member 1 and are sustained by a shaft or pin 10 which is secured in the printing member 1 and which extends transversely to the direction of the shaft 2. Each type disk 6, therefore, is capable of adjustment about an axis transverse to the axis of rotation of the printing member. With this construction it will be seen that by turning the various type disks 6 about the shaft 10 any printing character on each disk can be brought into the peripheral line of the printing member 1, this being the printing position of the type.

The work or material to be printed is shown at 11 and it is placed on the bed 4. As the printing member 1 rotates it acts to feed the work 11 across the bed 4 and at the same time the adjusted type 7 are brought into contact with the upper face of the work 11 and thus an impression is made thereon. I prefer to employ a presser or feed roll 12 to assist in feeding the work across the bed. 10 This roll is shown as journaled beneath the bed 4 in yieldingly-sustained bearings 13 that are movable vertically in suitable ways 14 and are acted upon by springs 15 which tend normally to hold the roll elevated. 15 Stops 16 are provided which limit the upward movement of the roll and in its normal position said roll is sufficiently below the printing member 1 so that said member will rotate freely without contacting with the roll. Whenever a piece of sheet material 11 is fed into the space between the roll 12 and the printing member 1, however, said material will be gripped between said member and roll and will be fed thereby during 25 which operation the impression will be made as will be obvious.

I have provided a construction whereby the material 11 can be placed on the bed adjacent the roll 12 and will remain there 30 until the printing member has reached substantially the position shown in Fig. 1, at which point the work 11 will be engaged by the printing member and will be fed forward thereby.

35 I have shown the printing member 1 as having a feeding projection 17 thereon adjacent the type disk 6. This projection may conveniently be made of rubber or any other friction material and is of such a length 40 that it will normally clear the roll 12, but when the piece of material 11 to be printed is placed in the position shown said projection will engage said material as the projection rotates in the direction of the arrow a 45 and will thus feed it forward.

It will be noted that the type which make the impression are arranged in a line along the periphery of the rotary member 1 so that these type will be brought successively 50 into engagement with the material 11. This is an advantage because the full pressure of the springs 15 is applied to each type in succession so that the effect is the same as would be caused if each type made its impression separately. As a result it is possible 55 to apply a heavy pressure to the printing type if desired even though the mark which is to be printed contains a large number of separate characters. In fact the number 60 of the separate characters does not in any way affect the pressure which is applied during the printing operation.

A device such as above described could be used merely for embossing leather or other

sheet material by the pressure of the type 65 against said material. If, however, a printing impression is to be made the type can be inked in any suitable way without departing from the invention. I have herein shown an inking roll 20 which is adapted to 70 be engaged by those type which are in printing position as the printing member revolves and which is journaled in suitable bearings 21 carried by the ink reservoir 22. Said roll 20 contacts with an ink-distributing roll 23 75 which operates in the ink reservoir and distributes the ink to the inking roll 20. This ink reservoir may be conveniently sustained on a suitable bracket or stand 24 or may be supported in any other appropriate 80 way.

I have shown in Fig. 4 a simple implement by which the individual type disks can be readily adjusted to bring any type thereon into printing position. This implement 85 which is shown at 25 has the head portion 26 adapted to fit into the notches 8 so that by inserting the implement into one of the exposed notches 8 of any of the disks, said disk can be turned about the shaft 10. The 90 disks are normally held in their operative position by holding pawls 27, one for each of the disks, said pawls being pivoted to the printing member at 28, and each having the head portion 29 adapted to engage one of 95 the notches 8. Each pawl is yieldingly held in position by a suitable spring 30. Each disk is shown as cut away on its periphery as at 31 to allow room for the holding pawls 27.

By using a rotary printing member it is 100 possible to make the successive impressions with extreme rapidity, and further it is possible to apply a high degree of pressure in making the impression from each type.

I have shown herein a simple embodiment 105 of my invention which is sufficient to illustrate the principle of it, but do not wish to be limited to the constructional details shown.

Having fully described my invention, 110 what I claim as new and desire to secure by Letters Patent is:—

In a printing machine, the combination with a bed for supporting the material to be printed, of a yieldingly-sustained presser 115 roll having its upper surface projecting through the bed, a rotary combined feeding and printing member situated directly above the presser roll but having its periphery separated therefrom a distance slightly less 120 than the thickness of the material to be printed, said combined feeding and printing member having a peripheral surface which engages the material and feeds it forward, means to rotate said member, a plurality of 125 type disks sustained by said rotary member for rotary movement about an axis extending at right angles to that of the rotary

member and having their operative type characters in the peripheral feeding surface of said rotary member, and a yielding feeding projection carried by said rotary member and extending beyond the periphery thereof in the line of the feeding surface and in advance of the type disks.

In testimony whereof, I have signed my name to this specification, in the presence of two subscribing witnesses.

FRED A. PUTNAM.
